UNITED STATES PATENT OFFICE.

WILLIAM H. TUOHY, OF EAGLE, WISCONSIN.

CONCRETE-MOLD.

1,111,197.

Specification of Letters Patent. Patented Sept. 22, 1914.

Application filed December 27, 1913. Serial No. 808,948.

To all whom it may concern:

Be it known that I, WILLIAM H. TUOHY, a citizen of the United States, and a resident of Eagle, in the county of Waukesha and State of Wisconsin, have invented certain new and useful Improvements in Concrete-Molds; and I do hereby declare that the following is a full, clear, and exact description thereof, reference being had to the accompanying drawings, and to the letters of reference marked thereon, which form a part of this specification.

This invention relates to improvements in concrete molds and it includes improved features of construction applicable to molds used for the construction of single walls, and also to improvements by which such molds are particularly adapted for use in the construction of walls and foundations of buildings and similar structures wherein the double wall construction is employed.

The object of my invention is to provide improvements in concrete molds embodying the general features set forth in my copending application filed on the 27th day of December, 1913, and bearing Serial No. 808,947, both with respect to the means for supporting and giving relative movement to the mold-boards of such molds, and with respect to means whereby the construction of double walls may be accomplished in an efficient and inexpensive manner.

My invention consists in the matters hereinafter described, more particularly pointed out in the appended claims, and illustrated in the accompanying drawings, in which—

Figure 1 is a view in side elevation of one form of concrete mold, constituting my invention; Fig. 2 is a top plan view of the mold illustrated in Fig. 1; Fig. 3 is a sectional view, taken on line 3—3 of Fig. 2; Fig. 4 is an enlarged detail plan view of a portion of the mold and wall, and showing the first position of the mold in forming a corner; Fig. 5 is a sectional view taken on line 5—5 of Fig. 4; Fig. 6 is a sectional view taken on line 6—6 of Fig. 4; and Fig. 7 is an enlarged detail plan view showing the position of the mold in completing a corner.

Referring to the drawings, showing a preferred embodiment of my invention, adapted for use in the construction of double walls, the concrete mold illustrated comprises, in general, two pairs of mold-boards 10, 11 and 12, 13. The pairs of mold-boards are separated by a space from each other, and each

pair comprises two upright mold-boards arranged to be normally maintained in parallel relation, and spaced apart to form a space therebetween adapted to receive concrete for the construction of each portion of the double wall. The mold-boards are supported in upright position by means of transversely extending frame members 14, provided with downwardly extending arms 15 to which said boards are secured. The arms supporting one mold-board of each pair are mounted in fixed relation to the frame members, and the arms supporting the other mold-board of each pair are pivotally mounted upon the frame members to permit a limited movement of the board supported thereby, for a purpose set forth in my separate application hereinbefore referred to. A manually operated means is further provided in connection with each frame member, for the purpose of simultaneously controlling the movement of the pivoted arms and the mold-boards secured thereto.

Referring now to Figs. 1, 2 and 3, wherein is shown a form of my device adapted for use in constructing walls of this double wall construction, an understanding of the features embodied therein may be had from the following description.

The mold boards 10, 11, 12, 13, respectively, are of equal length and have their upper and lower margins in parallel relation. The spaces between the boards 10, 11 and 12, 13 are preferably of equal width, and the distance between the inner boards 11 and 12 corresponds with the desired width of the space between the parts of the double wall, to be formed by the use of the device.

The upper margins of the mold-boards, by preference, lie in substantially the same horizontal plane. The lower margins of the outer mold-boards 10 and 12, however, project some distance below the lower margins of the inner mold-boards 11 and 12, as shown in Fig. 3. The purpose of this construction will be hereinafter pointed out.

The frame members 14, 14, by means of which the mold-boards are supported, extend transversely of the said mold-boards and are spaced apart at a suitable distance for properly supporting the boards, and for operating the mold.

Each frame member comprises a rectangular structure consisting of pairs of horizontal bars 15 and 16 arranged in parallel relation one above the other, and rigidly con-

nected together at their ends by means of vertical connecting members 17. The said connecting members extend between each pair of horizontal bars 15 and 16 and act to hold the said bars at a distance apart to form a space between them. A plurality of rivets 18 extend through the ends of the bars, completing the rigid structure of the frames 14.

10 Each of the frame members 14 supports a series of vertical arms 19, 20, 21 and 22, said arms extending downwardly below the lowermost frame bar 16 and supporting at their lower extremities the several mold-boards, there being provided suitable means for securing said arms to the outer faces of the mold-boards. Two of these arms, namely 19 and 20, are secured in fixed relation to the frame and extend between the 15 upper and lower horizontal bar members 15 and 16; the same being rigidly held in position by means of a plurality of bolts 23 extending through said bar members 15 and 16 and the upper and mid-portions of said 20 arms. The remaining arms 21 and 22 are secured to the frame members in a manner to permit them to be oscillated through a limited distance. The arm 21 is pivoted to the lower horizontal bar members 16 by 25 means of a pivot bolt 24 and projects a distance above the upper bar members 15. The arm 22 in like manner is pivotally mounted between the lower bar members 16 by means of a pivot bolt 24, but terminates between the 30 upper horizontal bar members 15. The arms 21 and 22 support the mold-boards 10 and 12, respectively, and are adapted to be adjusted for the purpose of swinging said boards through a limited distance, in a direction to and from the boards 11 and 13.

40 For the purpose of actuating the pivoted arms 21 and 22, I employ mechanism as follows: Rigidly fixed to the frame members 14, is an arm 25 which projects above the upper horizontal bar members 15 and terminates in horizontal alinement with the upper extremity of the arm 21. The fixed arm 25 is located between the movable arms 21 and 22 and has attached to it one end of a turn-buckle 26 of ordinary construction. The other end of said turn-buckle is secured to the upper extremity of the pivoted arm 21. The said arms 21 and 22 are connected together by means of a horizontal connecting link 27, secured to said arms immediately below the upper horizontal bar members 15. By revolving the turn-buckle in the proper direction the same may be expanded or contracted in a manner well known, acting to 45 transmit a movement to the upper end of the movable arm 21 to swing the same about its pivot bolt 24. This movement is simultaneously transmitted to the arm 22 through the medium of the connecting member 27. 50 By this arrangement the movable arms 21

and 22 remain constantly parallel and are controlled simultaneously by the manipulation of the turn-buckle 26.

The operation of constructing a wall of the before mentioned double-wall construction, is accomplished by the repeated use of the device hereinbefore described, and in the following manner: In Figs. 1, 2 and 3 is shown a portion of a wall 30 already completed, with the mold secured thereto and in position to receive concrete for the formation of a section of the wall to be superimposed upon the said completed portion of the wall. To secure the mold in position the turn-buckle is manipulated so that the movable mold-boards 10 and 12 are swung in a direction away from the stationary mold-boards 11 and 13, respectively, as shown in the dotted line of Fig. 3. By this operation the space between the pairs of mold-boards is increased sufficiently to allow the upper portions of the already completed portion of the wall to pass between the boards. The device is placed in position with the lower margins of the outer mold-boards slightly overlapping the outer surface of each wall portion; the margins of the inner mold-boards, by preference, coinciding with the adjacent upper and inner margins of the wall. Now, by again manipulating the turn-buckle the movable mold-boards are drawn inwardly against the outer faces of the wall portions, the result being that the mold becomes firmly clamped to the wall and in a position to be 55 filled with concrete in the usual manner. The engagement of the outer mold-boards with the wall is sufficient to retain the mold firmly in position and for that reason it is unnecessary that the inner mold-boards should extend downwardly in a manner to overlap the inner surfaces of the wall. The concrete having hardened sufficiently, the mold is released from its clamping engagement with the wall by manipulating the 60 turn-buckle to swing the boards 11 and 12 outwardly in the manner stated. The mold may now be advanced to a position where the ends of the mold overlap the ends of the wall portions just completed, the mold 65 clamped in that position, and the operation again repeated to form the next succeeding section.

A mold provided with mold-boards of equal length, as illustrated in Figs. 1 to 3, is necessarily limited in its use to the construction of continuous linear walls having no corners, but in constructing, with the mold-boards shown in said Figs. 1 to 3, walls meeting at an angle, it will be necessary to 70 provide additional molds for the purpose of forming the corners. In order to avoid the necessity of providing specially designed molds for forming corners or intersections, I provide, as a further feature of my invention, 75

tion, a mold embodying such features as to render it suitable for successfully overcoming the objectionable feature mentioned in the forming of intersections, without interfering at the same time with its adaptability for use in forming the straight or continuous portions of the wall. This purpose is accomplished by the addition of several novel features that are shown in Figs. 4 to 5; it being understood that the construction of the mold in this instance is like that hereinbefore described, except with regard to the features hereinafter pointed out. To accomplish the purpose desired, I provide two pairs of mold-boards 31, 32 and 33, 34, of which the boards of at least one pair, 31 and 32, extend or project at their ends a predetermined distance beyond the extremities of the other pair of mold-boards 33 and 34. In 10 the preferred construction shown (see Figs. 4 and 7), one pair, 31 and 32, of the mold-boards is made longer than the other pair, and projects at both ends beyond the ends of the other pair. The distance that the ends 15 of said pair of mold-boards 31, 32 projects beyond those of the other pair is dependent upon the thickness of the wall portions and the space separating them, but in any particular instance the distance is substantially 20 equal to or slightly greater than the distance separating the walls plus the thickness of one of the wall portions. At the adjacent extremities of the pairs of mold-boards and at one end of the mold, I provide gate-members 35, 35 (Figs. 4 and 6), which may be 25 removably inserted at the ends of and between the mold-boards, the same acting to provide a vertical end face at one of the ends of each section of the wall formed by the 30 mold.

As a preferable construction for the gate-members and means for removably securing them in place, the ends of the mold-boards are provided with angle members 36, secured to the outer faces of the boards. The 35 angularly bent portion of said angle members project inwardly toward each other and at a distance beyond the ends of the boards. In this manner a vertical space is formed between the said bent portions of the angle members 36 and the ends of the boards. The gate-member, preferably rectangular in shape, is provided with metal flanges 37, secured to the lateral margins of the outer 40 faces of the gate-member and projecting outwardly therefrom, and adapted to engage the said spaces formed by said angle members 36. At the upper portions of the said gate-members, are provided stops 38, adapted to engage the upper margins of the mold-boards, and acting to limit the downward movement of the gate-members, within the spaces. These stops are preferably formed by bending an upwardly extending portion 45 of the flange members 37 at right angles thereto. In addition to the gate-members, I provide the outer board 34 of the shorter pair of mold-boards with a rectangularly shaped rabbet 39 (Fig. 6), located in the lower margin of the board and preferably formed by removing a rectangular portion of the board adjacent to its end. The length of the rabbet is slightly greater than the thickness of the wall portion to be formed thereby and of a height equal to the distance 50 the said board overlaps the wall when the mold is clamped in horizontal position thereto. Rabbeting the mold-board in this manner has the effect of reducing the end portion of said board throughout the rabbeted portion to a height equal to that of its companion, the mold-board 33. The purpose of the rabbet will be apparent as I proceed with the description of the operation of the mold in 55 constructing or forming the intersection of two walls.

Describing the operation of joining the portions of a wall, intersecting at right angles, it is to be assumed that the portions 40 and 41 have already been constructed and 60 a superimposed section is to be formed. To perform the first step in the operation of constructing the intersection or corner, the mold is claimed to one of the intersecting portions of the wall, in a manner already suggested, and in such position that the ends of the mold-boards project slightly beyond the ends of the wall portion to which the mold is clamped and likewise beyond the portion of the wall intersecting the same at 65 right angles thereto, as shown in Fig. 4. The placing of the mold in this position is made possible by the increased length of the outer pair of mold-boards 31 and 32 and also by reason of the presence of the rebate 70 39 in one of the shorter pair of mold-boards 34, in that the intersecting portion of the wall 41 is embraced by the recess, thus permitting the end of the board to extend over the said wall portion and the mold to assume its proper horizontal position, which otherwise would not be possible, owing to interference of the said intersecting portion. Having clamped the mold in position, the gate-members are inserted in the ends 75 of the mold-boards for the purpose of forming the end surface of the section to be formed. By reason of the fact that the mold-boards project beyond the ends of the wall, as suggested, the gate-members may be 80 placed in position, and the alinement of the inner faces of the gate-member with the outer faces of the intersecting wall portion is assured. The mold is now ready to receive the concrete to form the superimposed 85 sections 42 and 43 (Fig. 5). After the concrete has hardened sufficiently the mold is removed and transferred to the intersecting portions of the wall and in a position at 90 right angles to the sections 42 and 43, just 95

formed. In this position, however, the opposite ends of the mold-boards, not provided with the gate-members, are placed in abutting relation to the sections 42 and 43 (Fig. 7), so that the space between the mold-boards extends up to the section just formed. In this position the mold is filled with concrete and when hardened produces a section joining the section previously formed, in a proper and workmanlike manner. By this arrangement of the mold-boards, it is seen that the construction of a wall having smooth and regular corners or intersections is easily and successfully accomplished, without the aid of any additional molds or equipment or in any way decreasing the suitability of the mold in the formation of the linear portions of the wall. In the construction of the straight or continuous portions of the wall, it is only necessary to overlap a greater extent the ends of the longer mold-boards upon the extremities of each preceding section to compensate for the additional length. The gate-members 35 may also be provided upon the form of mold provided with mold-boards of equal length (Figs. 1 and 2), for the purpose of forming spaces or openings in the wall, where it is desired to place windows or doors in the wall. In this instance, the gate-members act to provide a smooth end surface to the sections of the wall terminating at either side of the opening formed.

A concrete mold, embodying the features 35 of my invention, has the advantage of being capable of easy and rapid adjustment and removal whereby the work can be accomplished with great speed and with comparatively small amount of labor and loss 40 of time. Its use eliminates the added expense and inconvenience of providing and manipulating special molds for forming corners and openings, as before pointed out.

The device herein illustrated and described may be variously modified in the details of construction without departure from the spirit of the invention, and for that reason I do not wish to be limited thereto, except so far as pointed out in the appended 50 claims.

I claim as my invention:

1. A concrete mold, comprising a plurality of pairs of mold-boards spaced apart from each other, the mold-boards of each 55 pair being spaced apart to receive concrete between them, a supporting frame transverse to said boards, a plurality of arms on said frame extending below the same and attached to said mold-boards, the arms supporting one of the mold-boards of each pair 60 having pivotal connection with the frame, a connecting member extending between said pivoted arms, and operative means connected with one of said pivoted arms, and adapted to effect the swinging movement of 65

all of said pivoted arms through the medium of said connecting member.

2. A concrete mold, comprising a plurality of pairs of mold-boards spaced apart from each other, the mold-boards of each pair being spaced apart to receive concrete between them, a supporting frame transverse to said boards, a plurality of arms on said frame extending below the same and attached to said mold-boards, the arms supporting one of the mold-boards of each pair 70 of mold-boards having pivotal connection with the frame, a turn-buckle attached at one end with the frame and at its opposite end with one of said pivoted arms, and adapted when expanded and contracted to effect the swinging movement of said last mentioned pivoted arm, and a link extending between said arm adapted to transmit said swinging movement from one to the 80 other of said pivoted arms.

3. A concrete mold, comprising pairs of mold-boards spaced apart from each other, the mold-boards of each of said pairs being spaced apart to receive concrete between them, a transverse supporting frame, pairs of arms on said frame extending below the same and attached to the outer faces of the mold-boards of each pair of mold-boards, one of each pair of arms having pivotal connection with the frame, a link connecting said pivoted arms, one of said pivoted arms projecting above the frame, a rigid arm secured to the frame and projecting above the frame, and a turn-buckle connected at one 90 end with said last mentioned pivoted arm and at its opposite end with said rigid arm and adapted when expanded and contracted to effect the swinging movement of all of 95 said pivoted arms.

4. A concrete mold, comprising a plurality of pairs of mold-boards spaced apart from each other, the mold-boards of each of said pairs being spaced apart to receive concrete between them, a transverse supporting frame consisting of upper and lower, rigidly connected, frame members, two pairs of arms connected with said frame, one of each pair of said arms being pivoted to the lower member of the frame, a link connecting said pivoted arms, and a turn-buckle connected at one end with said frame and in operative connection at its opposite end with one of said pivoted arms above the pivot of the same, and acting on all of the pivoted arms 100 to swing the same into and out of operative position.

5. A concrete mold, comprising two pairs of mold-boards spaced apart from each other, the mold-boards of each of said pairs being spaced apart to receive concrete between them, a transverse supporting frame consisting of upper and lower, rigidly connected, frame members, two pairs of arms connected with the upper and lower mem- 115 120 125 130

bers of said frame, one of each of said pairs of arms being pivoted to the lower member of said frame, a link connecting said pivoted arms located adjacent to the upper member of the frame, and a turn-buckle connected at one extremity to the frame and at its other end with one of said pivoted arms, said turn-buckle being adapted, when contracted and expanded, to swing the pivoted arms inwardly and outwardly.

6. A concrete mold, comprising two pairs of mold-boards spaced apart from each other, the mold-boards of each of said pairs being spaced apart to receive concrete between them, the lower margin of one of the mold-boards of each pair terminating in a plane below that of the lower margins of the other mold-board of each of said pairs, a transverse frame member, pairs of arms on said frame member extending below the same and attached to said pairs of mold-boards, one arm of each pair having pivotal connection with the frame and in operative connection with each other, and means mounted on said frame and in operative connection with one of said pivoted arms, adapted, when expanded and contracted, to effect the swinging of all of said pivoted arms.

7. A concrete mold, comprising two pairs of mold-boards spaced apart from each other, the mold-boards of each pair being spaced apart to receive concrete between them, and the outer mold-boards of each pair extending downwardly below the inner mold-boards of each pair, a frame member, pairs of arms on said frame member extending downwardly and attached to said mold-boards, one arm of each pair having pivotal connection with said frame member and attached to the inner mold-board of one pair and to the outer mold-board of the other pair of said mold-boards, a link connecting said pivoted arms, and means connected with one of said pivoted arms and with said frame, acting to effect swinging movement of one of said pivoted arms, said link acting to transmit the swinging movement to the other of said pivoted arms.

8. A concrete mold, comprising two pairs of mold-boards spaced apart from each other, the mold-boards of each pair being spaced apart to receive concrete between them, and the outer mold-boards of each pair extending downwardly below the inner mold-boards of each pair, a frame member, pairs of arms on said frame member extending downwardly and attached to said mold-boards, one arm of each pair having pivotal connection with said frame member attached to the inner mold-board of one pair and to the outer mold-board of the other pair of said mold-boards, one of said pivoted arms extending above the frame member, a link connecting all of said piv-

oted arms, a rigid arm extending upwardly above said frame, and a turn-buckle attached to the said rigid and upwardly extending arm and to the upper end of said pivoted arm which extends above the frame member.

9. A concrete mold, comprising pairs of mold-boards spaced apart from each other, the outer mold-boards of each pair extending below the inner mold-boards of each pair, a transversely extending frame comprising upper and lower frame members, each consisting of two parallel bars spaced apart and rigidly connected at their ends, stationary arms secured between the bars of the upper and lower frame members and attached to one of the mold-boards of each pair, pivoted arms mounted between the lower bar of the frame members and attached to the other mold-board of each pair, a link connecting all of said pivoted arms, and means for swinging the mold-boards attached to the pivoted arms, comprising a turn-buckle attached at its ends to one of the pivoted arms and the frame, said link acting to transmit the swinging movement to the other of said pivoted arms.

10. A concrete mold, comprising pairs of mold-boards spaced apart from each other, the outer mold-boards of each pair extending below the inner mold-boards of each pair, a transversely extending frame comprising upper and lower frame members, each consisting of two parallel bars spaced apart and rigidly connected at their ends, stationary arms extending between the bars of the upper and lower frame members and attached to one of the mold-boards of each pair, pivoted arms mounted between the lower bar of the frame members and attached to the other mold-board of each pair, one of said pivoted arms extending between the bars of the upper frame member and projecting above the same, a link connecting said pivoted arms, a rigid arm extending above the frame, and means for swinging the mold-boards attached to the pivoted arms, comprising a turn-buckle connected at its ends with the upwardly extending rigid arm and with one of said pivoted arms.

11. A concrete mold, comprising pairs of mold-boards spaced apart, each pair being adapted to receive concrete between them, a transverse frame, arms extending downwardly from said frame and secured to said boards, the boards of one of said pairs extending beyond the ends of the boards of the other of said pairs of mold-boards, and at least one of the mold-boards of each pair being provided with a *rabbet* forming thereon an end portion of reduced width.

12. A concrete mold, comprising pairs of mold-boards spaced apart from each other, the mold-boards of each pair being adapted

- to receive concrete between them, a transverse frame, arms extending downwardly from said frame and secured to said boards, the boards of one of said pairs extending at 5 both ends thereof beyond the ends of the boards of the said pairs, the outer mold-board of one of said pairs being provided with a rabbet located adjacent to its end and forming an end portion of reduced width.
- 10 13. A concrete mold comprising pairs of mold-boards spaced apart, each pair being adapted to receive concrete between them, a frame member, arms extending downwardly from said frame and secured to said boards, 15 the outer mold-board of each pair extending below the inner mold-board of each pair, at least one of said outer mold-boards being provided with a rabbet in the lower margin.
14. A concrete mold comprising pairs of mold-boards spaced apart, each pair being adapted to receive concrete between them, a transverse frame, arms extending downwardly from said frame and secured to said boards, transverse gate members, and means 20 for removably securing said gate members between the adjacent ends of the pairs of mold-boards, at least one of said mold-boards being provided with a rabbet located adjacent to a gate member.
- 30 15. A concrete mold, comprising pairs of mold-boards spaced apart, each pair being adapted to receive concrete between them, a transverse frame, arms extending downwardly from said frame and secured to said 35 mold-boards, the outer mold-boards of each pair extending below the inner mold-board of each pair, transverse gate members, means for removably securing said gate members between said pairs of mold-boards, 40 at least one of the outer mold-boards being provided in its lower margin with a rabbet forming a portion substantially equal in width to the adjacent inner mold-board.
16. A concrete mold, comprising pairs of mold-boards spaced apart from each other, the mold-boards of each pair being adapted 45 to receive concrete between them, a transverse frame, arms extending downwardly from said frame and secured to said boards, 50 the boards of one of said pairs extending at both ends thereof beyond the ends of the boards of the other of said pairs, transverse gate-members, and means for removably securing said gate-members between adjacent 55 ends of the pair of mold-boards, at least one of said mold-boards being provided with a rabbet located adjacent to a gate-member and forming an end portion of reduced width.
17. A concrete mold, comprising pairs of mold-boards spaced apart from each other, 60 the mold-boards of each pair of mold-boards being adapted to receive concrete between them, and the outer mold-board of each pair extending downwardly below the inner mold-board of each pair, a transverse frame, 65 arms on said frame extending downwardly and secured to said mold-boards, one pair of said mold-boards extending at both of its ends beyond the ends of the boards of the other of said pairs, transverse gate-members, means for removably securing said gate-members between adjacent ends of said pairs of mold-boards, one of the boards of the shorter of said pairs of mold-boards being provided with a rabbet located adjacent 70 to the gate-member, forming an end portion of a reduced width substantially equal to that of the inner mold-board of said shorter pair of mold-boards.
18. A concrete mold, comprising pairs of mold-boards spaced apart from each other, 75 the boards of each pair of mold-boards being adapted to receive concrete between them, and the outer mold-board of each pair extending downwardly below the inner mold-board of each pair, a transverse frame, 80 arms on said frame extending downwardly and secured to said mold-boards, the boards of one pair of said mold-boards extending at their ends beyond the ends of the boards of the other of said pairs of mold-boards, transverse gate-members, and means for removably securing said gate-members between adjacent ends of said pairs of mold-boards, the outer mold-board of the shorter 85 of said pairs of mold-boards being provided with a rabbet located adjacent to the gate-member, forming an end portion of reduced width substantially equal to the width of the inner mold-board of said shorter pair of 90 mold-boards.
- In testimony, that I claim the foregoing as my invention I affix my signature in the presence of two witnesses, this 19th day of Dec., A. D. 1913.
